ATTORNEY.

UNITED STATES PATENT OFFICE.

WILLIAM E. KELLY, OF CLEVELAND, OHIO.

TOILET INSTRUMENT.

1,425,776.

Specification of Letters Patent. Patented Aug. 15, 1922.

Application filed December 8, 1919. Serial No. 343,320.

To all whom it may concern:

Be it known that I, WILLIAM E. KELLY, residing at Cleveland, county of Cuyahoga, and State of Ohio, have invented a new and 5 useful Toilet Instrument, of which the following is a specification.

My invention relates to toilet instruments adapted to operate upon accessible surfaces of the body.

10 The object of my invention is to provide a convenient and efficient instrument to remove objectionable matter from the surface of the body and to promote the health thereof.

15 I attain this object by the instrument illustrated in the accompanying drawings in which Fig. I is a general side view of the instrument partly broken away to show interior parts; Fig. II is an end view of Fig. 20 I at A; Fig. III is an end view of Fig. I at B; and Fig. IV is a section on line 4—4 of Fig. I. In order to show the several members clearly, the drawings are not drawn to any particular scale or proportion.

25 Similar reference characters refer to similar parts throughout the views.

Ear troubles, such as excessive wax in the ear, or hardening of this wax, or dryness of the tympanum, as well as skin troubles and 30 blemishes such as blackheads, pimples, or other foreign matter frequently found upon or in the pores of the skin are detrimental to health and unsanitary and the general welfare imposes that such troubles be reme-

35 died. The means now at hand for such purposes are cumbersome and time consuming. For instance, blackheads are now removed with tweezers or the finger nails which leaves a marred skin and may cause infec-

40 tions; wax is now removed from the ear with spoons which offer no protection to the tympanum of the ear; ears are lubricated by saturating cotton with a lubricant and inserting this cotton into the ear and leaving 45 it there for some time which is not only inconvenient but also objectionable since this cotton frequently falls out and soils linens etc. and subjects the ear to a sudden change of temperature (kept warm by the cotton 50 while in the ear but equivalent to a draft when out) and the trouble may be aggravated instead of eliminated or relieved.

The present invention aims to overcome 55 the objectionable features found in present practice in regards to the matters pointed

out as well as others not specifically mentioned herein but being analogous and provide a handy and serviceable instrument for that purpose.

Referring now particularly to the drawings:

The body 1, made of suitable material and form, has a threaded opening in its front end and, adjacent thereto, has the chamber 2; the purposes whereof will appear hereinafter. On the other end, the body 1 has the head 3 and, adjacent thereto, the neck 5. It will be seen that the front end of the body 1 has the beveled face 6 which acts similar to a valve seat as will appear hereinafter.

60 The cap 7, made of suitable material and form, has a threaded opening in its front end and, adjacent thereto, has the recess 8; the purpose whereof will appear hereinafter. On the other end, the cap 7 has the hoe 9 65 as shown and, adjacent thereto, has the neck 10. The hoe 9 should have a very thin edge 11, but this edge should not be sufficiently sharp to cut. The front end of the cap 7 70 also has a beveled surface which corresponds 75 to the bevel surface 6 on the body 1. and fits to the bevel surface 6 on the body 1.

The tube 12, made of suitable material, is threaded on the outside to fit the threaded opening in the body 1 and in the cap 7. The tops of these threads should be well rounded 80 and should not be sufficiently sharp to cut or in any manner injure whatever part of the body it may come in contact with. I prefer to spin the threads on the tube and form them similar to the Whitworth form of 85 thread.

90 After the parts are made as shown and described, they are assembled as follows: A wick 13, of sufficient length to project some distance outside of each end of the tube 95 12, is placed in the tube 12 as shown in Fig. I. The body 1 is then held upright, with the threaded opening up, and a sufficient quantity of the lubricant selected or required for any particular purpose is poured 100 100 into the tube 12. It is also advantageous that the wick 13 be now saturated with this lubricant to the end that the otherwise dry wick will not absorb a certain quantity of the lubricant and thereby partially empty the chamber 2. The tube 12, with the wick 13, is now screwed into the body 1 sufficiently deep to permit a portion thereof to project outside of the body 1 as clearly seen in Fig. I. The cap 7 is now 110

screwed on to this projecting portion of the tube 12. It will be seen that the bevel face 6 on the body 1 fits to the bevel face on the cap 7; therefore, when the cap 7 is screwed down tight, a leak proof joint will be formed at this juncture. The instrument is now ready for use.

The operation of this instrument for lubricating the tympanum or other interior parts 10 of the ear is as follows: The chamber 2 being filled with the lubricant required or desired, unscrew the cap 7, insert the end 14 of the wick 13 into the opening of the ear and push inward until the end of the wick 15 13 touches the tympanum, let it rest there a short time to permit the tympanum to absorb some of the lubricant which seeps through the wick, then remove the instrument from the ear, screw on the cap, and 20 lay aside for future use.

The head 3 is used, principally, as a scraper to remove wax or other foreign or undesirable substance from the ear for instance. This head 3 should be smooth to 25 the end that the same may not injure the tympanum or whatever other parts it may come in contact with. The manner of using this part of the apparatus independently appears obvious.

30 The operation of the hoe 9, to remove blackheads for instance is as follows: Apply the edge of the hoe at the base of the blackhead, then gently and slowly press downwardly and toward the blackhead whereupon the same will be lifted out of its cavity 35 without injuring or marring the skin. Similar to the head 3, this hoe 9 should also be smooth to prevent injury.

The operation of the instrument as a 40 whole, in connection with ear troubles, is as follows: We will suppose that the ear requires cleaning and lubricating; first use the head 3 to remove whatever foreign substance should be removed; if it is found (as it frequently is) that this substance is very hard and caked so that the head 3 will not remove the same owing to the roundness of its edge or the inability to reach certain parts of the ear therewith, use the hoe 9 to finish the 45 cleaning process; then lubricate with the wick as above described.

It will be seen that the present invention provides an efficient and long needed toilet instrument which is convenient of operation, 50 substantially leakproof, convenient to carry,

or lay down, always ready for use, and does not get out of order easily.

It is thought that the foregoing description and the accompanying drawings are sufficiently clear to be readily understood 60 and to enable others to understand the present invention and to devise modifications thereof within the scope of the appended claims.

Therefore, without limiting myself to the 65 precise construction shown and described, I claim—

1. An apparatus of the character described comprising a case provided with a chamber to hold a lubricant, a tube within 70 said case, a wick in said tube and one end thereof in communication with said lubricant and the other end thereof projecting outside of said case, and a cap on said case.

2. A new article of manufacture, comprising a case formed with an opening in one end thereof and with a reduced portion on the other end thereof and with a head on the end of this reduced portion, a lubricant in said opening, a wick in said opening and one 80 end thereof in communication with said lubricant and the other end thereof projecting outside of said case, and a cap on said case to close said opening.

3. A new article of manufacture, comprising a case formed with an opening and with a reduced portion at this open end and with a bevel surface between this reduced portion and the main body of the case, a lubricant in said opening, a wick in said opening 85 and one end thereof in communication with said lubricant and the other end thereof projecting outside of said reduced portion, and a cap formed with an opening adapted to said reduced portion of the case and with a bevel surface adapted to said bevel surface 90 on the case to form a tight joint between said case and said cap.

4. An apparatus of the character described comprising a case provided with a chamber 100 to hold a lubricant and with a threaded opening in communication with said chamber, a threaded tube in said threaded opening and projecting outside of said case, a wick in said tube and one end thereof in 105 communication with said lubricant and the other end thereof projecting outside of said tube, and a threaded cap on said tube and adapted to seal said case.

WM. E. KELLY.
